UNITED STATES PATENT OFFICE.

HARRY BARRINGER COX, OF HARTFORD, CONNECTICUT.

THERMO-ELECTRIC GENERATOR.

SPECIFICATION forming part of Letters Patent No. 529,711, dated November 27, 1894.

Application filed January 31, 1894. Serial No. 498,660. (No model.)

To all whom it may concern:

Be it known that I, HARRY BARRINGER COX, of Hartford, in the county of Hartford and State of Connecticut, have invented certain new and useful Improvements in Operating Thermo-Electric Generators; and I do hereby declare that the following is a full, clear, and exact description of the invention, which will enable others skilled in the art to which it appertains to make and use the same, reference being had to the accompanying drawings, and to the letters and figures of reference marked thereon, which form part of this specification.

15 This invention relates to certain improvements in generating thermo electric energy and in machines for producing the same.

The object of this invention is to provide an improved method of storing heat from a central source of supply and supplying the heat equally to all portions of the electric generator.

20 A further object of this invention is to store and use the heat of a central source of thermal energy by means of liquid conduction whereby boiling water, oil or any other chemical solution or molten metal is used as a conducting and storing medium for conveying the heat from the central source of energy to the complete pile.

25 The invention consists in the improved method herein set forth and in certain novel features of construction and in combination of the parts described and pointed out herein-
30 after.

35 Referring to the accompanying drawings:— Figure 1, is a top plan view of a battery of thermo-electric generators, a portion of the outer casing being broken away at one end. Fig. 2, 40 is a vertical sectional view through the same.

In the drawings the reference letter *a*, indicates the thermo-electric generators, three being here shown, suitably coupled together by wires 2, in water tight tubes 3.

45 Each generator is built up in any suitable and desirable manner, preferably of series of rings of thermo-couples electrically connected together in the usual manner and built up in cylindrical form.

50 The generators are here shown located parallel and close together and inclosed in a casing or water jacket *b*, which is arranged to be

supplied with cold water to maintain the outer surfaces or junctions of the thermo couples of the generators cool and to supply the cooling medium therefor. These generators are arranged in this casing which forms a single water jacket as here shown for all generators so that their entire outer surfaces are maintained cool, suitable inlet and outlet pipes 60 being provided for the water jacket.

e, indicates a liquid tank or receptacle here shown located beneath the generator and provided with the vertical pipes or conduits *f*, extending up therefrom and filling the central openings of the generators. These vertical pipes or conduits are preferably closed at the top as shown and can be provided with a pressure gage or thermometer or both if desired. A suitable source of heat such as *g*, is provided to heat the liquid in the main tank hot so that the liquid in the tank stores up the heat from said source and the liquid in the vertical stand pipes within the generators maintain the inner spaces of the generator 70 hot and at an even temperature. By employing this means for maintaining the differences in temperature in the generators it will be observed that an extremely simple and compact apparatus can be made and that an apparatus very efficient in construction and operation is employed and that the machine will

75 be very durable and lasting as the direct impingement of the flame against the inner surfaces of the generators is avoided with the consequent disadvantages thereof. Furthermore an even heat is supplied to all portions of the inner face of the generator in such a manner that the temperatures can be maintained at the point desired. It should also be noted 80 that the heat from any suitable source can be stored in the liquid conductor and thereby imparted to the inner surfaces of the generator evenly and for an extended period, even though the source of heat may vary in temperature and inten- 85

90 It should be noted that the liquid conductor to apply the heat to the inner surface of the generator is entirely distinct from the cooling liquid at the exterior of the generator and that the heating medium forms no part of the electric circuit or portions of the generator. 95

I do not wish to limit myself to any particular construction shown here, or to any pe- 100

cular liquid heat conducting and storing me-
diuns as the specific constructions shown are
merely intended as a practical illustration of
a suitable means for carrying out this inven-
tion. It should also be noted that this inven-
tion is not limited to the employment of sev-
eral generators, but that it can be employed
with a single generator, nor is it limited to
the employment with a generator having the
outer cooling water jackets as my present in-
vention comprises broadly the storage and
use of a liquid conveyer of thermic energy
and thermo electric generators.

It is evident that various changes might be
made in the forms, arrangements and con-
structions of parts described without depart-
ing from the spirit and scope of my inven-
tion. Hence I do not wish to limit myself to
the exact construction herein set forth but
consider myself entitled to all such changes
as fall within the spirit and scope of my in-
vention.

Having thus fully described my invention,
what I claim as new, and desire to secure by
Letters Patent of the United States, is—

1. A thermo-electric generator having a
confined body of liquid inclosed within its in-
terior and means, substantially as described,
for heating said body of liquid, substantially
as set forth.

2. A thermo-electric generator having an
exterior cooling jacket and an interior liquid
body and means for heating said body of
liquid.

3. A thermo-electric generator having a 35
surrounding water jacket, a liquid tank be-
neath the same provided with heating means
and having a stand pipe extending upwardly
through the center of the electric generator
so that the heat stored in said tank will be 40
conveyed to the inner surface of the generator.

4. A series of electric generators suitably
coupled together electrically, a single water
jacket inclosing said generators to cool the
outer surfaces thereof, a liquid tank located 45
beneath the generator provided with the
stand pipe extending upwardly through the
center thereof, as and for the purpose set
forth, and means to heat said tank, substan-
tially as described. 50

5. A thermo-electric generator having a
stationary confined body of liquid within the
same to heat the inner face of the pile, sub-
stantially as described.

6. A thermo-electric generator having a 55
cooling agency for the cool junctions of the
thermo-couples and a confined body of liquid
against the heated junctions of the couples,
and heating means for said confined body,
whereby heat is stored therein as set forth. 60

In testimony that I claim the foregoing as
my own I affix my signature in presence of
two witnesses.

HARRY BARRINGER COX.
